UNITED STATES PATENT OFFICE

RICHARD BERNHARD, OF ALLENTOWN, PENNSYLVANIA, ASSIGNOR TO TRAYLOR ENGINEERING & MFG. COMPANY, OF ALLENTOWN, PENNSYLVANIA, A CORPORATION OF PENNSYLVANIA

CRUSHER

Application filed May 24, 1929. Serial No. 365,732.

My said invention relates to improvements in gyratory crushers of the type disclosed in an application for Letters Patent of the United States filed by me on the 18th day of 5 August, 1928, Serial Number 300,549.

The invention aims to provide an improved form of balancing or yielding supporting means for the head or crushing cone which will protect the crusher against breakage 10 when non-crushable material (such for example as tramp iron), enters the hopper, and against excessive stress if the crusher should become packed with clayey material.

The invention further aims to provide 15 means which will enable the head to be adjusted without interrupting the operation of the machine.

With these and other objects in view, the 20 invention includes the novel features of construction and arrangement and combination of parts hereinafter described, what I regard as my invention being defined by the claims appended hereto.

In order that the invention may be more 25 readily understood reference is made to the accompanying drawings in which:

Figure 1 is a central vertical section through the crusher.

Fig. 2 is a horizontal section on line 2—2 of 30 Fig. 1.

Fig. 3 is a section through the upper end of the shaft, spider, and associated parts on line 3—3 of Fig. 2.

Fig. 4 is a detail section on line 4—4 of 35 Fig. 1.

Fig. 5 is a central vertical section through a modified form of crusher.

Fig. 6 is a section on line 6—6 of Fig. 5, and

Fig. 7 is a detail section on line 7—7 of 40 Fig. 5.

Fig. 8 is a detail elevation of the spring cage and associated parts.

Referring by reference characters to these 45 drawings, the numeral 1 designates the shaft of the crusher which carries a crushing cone 2 provided with a crushing mantle 2^a. The shaft is suspended at its upper end by means hereinafter more fully described, by the supporting spider 4 (such means permitting gyratory movement of the depending shaft),

which spider, in the form shown in Fig. 1 is formed or cast integral with a top shell part 5 to the inner face of which the lining concave sections 6 are applied. This shell part 5 rests upon and is bolted to a bottom shell 7 which contains the discharge, diaphragm, and eccentric bearing.

As these latter parts and the means for operating the eccentric are substantially the same as shown in my aforesaid application 60 and also in my prior Patent 1,336,015 dated April 6, 1920, a more detailed description thereof herein is deemed unnecessary.

The upper end of the shaft 1 carries a sleeve 8 which is slightly tapered upwardly on its exterior to correspond to the gyratory movement of the shaft, and connection between the sleeve and shaft is effected by the customary contracting nut 9 screwed on to the reduced upper end 1^a of the shaft, the exterior surface of the nut being downwardly tapered to coact with the correspondingly tapered inner wall of the upper end of the sleeve 8. Said sleeve is surrounded by a floating bushing 10 which has at its lower end an inwardly extending annular flange or shoulder 10^a which underlies the lower end of the sleeve 8 and supports the same (and thereby the gyratory shaft) through the intermediary of the wear ring 11.

Said floating bushing has an outwardly projecting flange 10^b at its upper end which overlies the arm terminals 12^a of a lever (or levers), 12 fulcrumed in a hollow portion of the spider 4 as clearly shown in Fig. 2. The portions of the lever arms 12 adjacent their ends 12^a are curved so as to be approximately concentric to the shaft and their ends are deflected upwardly and provided with convex bearing edges to contact with the flange 10^b as shown by dotted lines in Fig. 1, against which they act with a sliding or cam action. Said lever arms are fulcrumed on pins set in the wall of the spider, portions of these pins projecting into the spaces between the floating bushing 10 and spider hub, and the arms being provided on their under sides with curved recesses 12^c to receive the exposed portions of the pins.

The opposite ends of levers 12 are connected 100

by bolt 14 with the eye of an eye bolt or rod 15 which depends through an opening 4^a and the spider and is held under the action of restraining springs which tend to hold the ends of the levers depressed and the gyratory shaft and cone elevated.

I preferably use a plurality of springs and to this end provide opposed spring seats 16 and 17 having openings through which the 10 rod 15 passes and a pair of springs 18 located on opposite sides of the rod and having their ends seated in the spring seats 16 and 17 and confined therebetween. Spring seat 16 has approximately wedge shaped bearing ribs 16^a on opposite sides of the rod which engage corresponding bearing recesses in the rib members 19 on the under side of the spider on opposite sides of the opening 4^a.

The lower end of the rod is threaded to receive a nut 20 which is provided with an operating lever or handle 21 by which it may be rotated to adjust the tension of the springs.

The spring seats are preferably provided with cage bolts 18^a passing centrally through the springs and slidably engaging openings in the spring seat 17. The spider is provided with an integral portion 4^b lying between the lever arms as shown in Fig. 2 from which figure it will be seen that the floating bushing is 25 maintained in axial position at all times.

It will be readily apparent from the foregoing description that I provide means for yieldably supporting the crusher shaft and cone whereby these are capable of yielding 35 under excessive stress, and furthermore, such means is capable of ready adjustment during the operation of the crusher.

Cover members 22 and 22^a are preferably provided for covering the upper end of the 40 shaft and sleeve assembly and the lever arms to exclude dust, etc.

The top of the shell portions 5 lying between the spider arms and which constitutes the feed hopper is provided with wear plates 45 23.

In a crusher of the type described, due to the fact that the head or cone is of larger diameter at its base than the concave, the shell portion 5 must necessarily be removed 50 before the cone and shaft may be lifted out when this is desired. By making the top shell and spider integral, this removal is simplified and there is a saving in weight and simplification and economy of manufacture.

Such construction, however, is suitable only for smaller sizes of crushers. For larger crushers, it is desirable to make the top shell and spider of separate parts.

Such construction is illustrated in Fig. 5 in 60 which the spider 4^x seats in recesses or bearing seats in the upper portion of the top shell 5^x, the spring rod passing through aligned openings in the bottom of the spider and corresponding seat portion of the shell.

In such heavier types, I prefer to provide

more springs, using preferably groups of four, and I preferably divide the springs transversely to provide upper and lower sets having their adjacent ends located in the oppositely facing bearing recesses or seats of a seat member 24 slidable on the rod 15^a and cage bolts which latter in this form are preferably located between the springs. 70

Having thus described my invention what I claim is:

1. In a gyratory crusher a concave shell, a spider carried thereby, a lever fulcrumed in the spider, a gyratory crusher shaft having its upper end rotatably supported from said lever, and means for adjusting the position of 80 said lever.

2. A gyratory crusher according to claim 1 in which the concave shell and spider are formed integral.

3. In a gyratory crusher a concave shell, a spider carried thereby, a lever fulcrumed in the spider, a gyratory crusher shaft having its upper end rotatably supported from said lever, spring means acting on said lever to hold the shaft elevated, and means for adjusting the action of said spring means. 85

4. In a gyratory crusher a concave shell, a spider carried thereby having a central bearing portion and hollow arm, a floating bushing guided in said bearing portion, a crusher shaft supported from said bushing, lever means fulcrumed in said hollow arm and operatively engaging said bushing, and adjustable restraining means acting on said lever means. 95

5. In a gyratory crusher a concave shell, a spider carried thereby having a central bearing portion and hollow arm, a floating bushing guided in said bearing portion, a crusher shaft supported from said bushing, lever means fulcrumed in said hollow arm and operatively engaging said bushing, and adjustable spring restraining means acting on said lever means. 100

6. In a gyratory crusher, a concave shell, a spider carried thereby having a central bearing portion and hollow arm, a floating bushing guided in said bearing portion, a crusher shaft suspended from said bushing, said bearing portion having recesses leading from said hollow arm to opposite sides of said floating bushing, lever arms fulcrumed on said spider and operatively engaging said bushing, and spring means acting on said lever arms. 110

7. In a gyratory crusher, a concave shell, a spider carried thereby having a central bearing portion and hollow arm, a vertically movable bushing in said bearing portion, said bearing portion having recesses on opposite sides of the floating bushing communicating with said hollow arm, said bushing having shoulder means at its upper end, lever arms having portions fulcrumed in said recesses and ends engaging said shoulder means, 115 125 130

adjustable spring means acting on said lever arms, and a crusher shaft suspended from said floating bushing.

8. In a gyratory crusher a concave shell, a spider carried thereby having a central bearing portion, a floating bushing guided in said bearing portion, a crusher shaft supported from said bushing, lever means of the first order engaging said bushing and overlying one of the arms of the spider, a rod connected to said lever means and depending through an opening in the spider arm, and adjustable restraining means for said rod.

9. In a gyratory crusher a concave shell, a spider carried thereby having a central bearing portion, a floating bushing guided in said bearing portion, a crusher shaft supported from said bushing, lever means of the first order engaging said bushing and overlying one of the arms of the spider, a rod connected to said lever means and depending through an opening in the spider arm, spring means interposed between said spider arm and the end of said rod, and means for adjusting the pressure of said springs.

10. In a gyratory crusher, a concave shell, a spider carried thereby having a central bearing portion and hollow arm, a vertically movable bushing in said bearing portion having an internal flange at its lower end, a sleeve within the bushing supported by said flange, a crusher shaft supported by said sleeve, said bearing portion having recesses on opposite sides of said bushing communicating with said hollow arm, lever arms in said hollow arm having portions projecting into said recesses, and fulcrumed therein, said bushings having shoulders overlying said lever arms, and restraining means acting on said lever arms.

11. A gyratory crusher according to claim 10 having pins inserted in openings in the sides of the bearing portion of the spider and projecting into the spaces beneath the lever arms to serve as fulcrums therefor.

In testimony whereof, I affix my signature.
RICHARD BERNHARD.
